UNITED STATES PATENT OFFICE.

FREDRICK TUCKER, OF LAFAYETTE, ALABAMA.

BUGGY-BODY.

1,343,068.

Specification of Letters Patent.

Patented June 8, 1920.

Application filed July 3, 1919. Serial No. 308,399.

To all whom it may concern:

Be it known that I, FREDRICK TUCKER, a citizen of the United States of America, residing at Lafayette, in the county of Chambers and State of Alabama, have invented new and useful Improvements in Buggy-Bodies, of which the following is a specification.

The object of the invention is to provide, 10 in combination with a buggy body, a locker wherein there may be kept the lap robes and various other articles it is customary to carry in a vehicle of this character. The locker also makes provision for the locking of the 15 whip by placing the butt of the same in the locker, there being means for engaging the whip and holding it in place when the locker is secured and locked.

While illustrated and described in a specific embodiment, the invention is not to be restricted to such embodiment. The right is reserved to make such changes and alterations as the actual reduction to practice may suggest, in so far as such changes or alterations 25 are compatible with the annexed claims.

In the accompanying drawings:

Figure 1 is a longitudinal vertical sectional view of a buggy body constructed in 30 accordance with the invention.

Fig. 2 is a horizontal sectional view of a buggy body taken below the plane of the back closure member of the lock.

Fig. 3 is a section on the line 3—3 of 35 Fig. 1.

Fig. 4 is a section on the line 4—4 of Fig. 1.

Fig. 5 is a section on the line 5—5 of Fig. 1.

As illustrated the buggy body 1 is constructed according to the usual plan, having the seat supporting means 2 disposed substantially at an intermediate point at its length. Below the seat supporting means 2 40 and extending to the rear end of the body the space comprehended thereby is designed to be employed as a locker and to this end a lid or cover 3 is hingedly attached to the seat support 2 at the rear and when closed lies 45 down on top of that portion of the body behind the seat support.

At the front of the seat support and hinged at the floor of the body there is a door 4 which swings up to a position of closure 55 when its free edge abuts the bead 5 attached to the seat support. The door 4 carries a

hasp 6 which engages a staple 7 carried by the seat support and when a lock, such as a lock 8 is attached to the staple, the door 4 is obviously secured in closed position. 60

The locking means for the door 4, herein shown as the lock 8, also serves as a locking means for the cover 3 on the under face of which adjacent the edge opposite from that which is hinged, there is attached a chain 9 which extends to the bottom of the body and is trained over a sheave pulley 10, the chain passing thence toward the front of the body and being trained over a sheave pulley 11 from which it passes through a suitable 65 opening formed in the door 4 adjacent its hinged end and thence passes upwardly to the staple 7 to have its eye 12 engaged over the latter before the lock 8 is attached to the hasp. The chain is of such a length that 70 when the eye is attached over the staple the cover 3 is held in closed position. In order that the cover may not be pried up at its side edges, the diagonally disposed chains 13 are provided and have one end connected to the 75 cover 3 adjacent the corners formed by the outer side edges and the rear edge, the other ends of the chain being connected into the chain 9 at a point above the sheave pulley 10. When it is desired to raise the cover 3, the 80 chain may be released from the staple 7 by disengaging its eye 12 therefrom. The cover may then be raised until the eye 12 is brought into engagement with the sheave pulley 11. This obviously will not permit 85 the cover 3 to be raised as high as it may sometimes be desired. There is therefore included in the chain 9 a snap hook 14 by means of which the chain may be separated into two sections. This will obviously permit 90 the cover 3 to be raised as high as is desired because that portion of the chain connected with it may be raised with it, leaving the remainder of the chain lying in the bottom of the buggy. 95

Carried by the door 4 and straddling the hasp 6 and the chain 9 adjacent the eye 12 there is a U-shaped member 15 which serves as a hand grip for opening the door 4 when the lock 8 is released. 100

To provide means for locking the whip usually carried with a buggy, there is set in the upper edge of the door 4 on one side of the hasp 6, an inverted U-shaped member 15' provided with flanges 16 lying flush with the 110 upper edge of the door 4 serving to secure the U-shaped member in place with the door.

When the door is opened the butt end of the whip may be inserted in the locker and the whip caused to lie in the U-shaped member 15'. When the door is closed, the U-shaped member 15' is so dimensioned that the butt end of the whip may not be drawn therethrough but to further insure the whip's being retained in the locker a hook 17 is provided and pivotally mounted on the inner 10 face of the door 4 by means of a screw 18, the pivot point of the hook being disposed below the horizontal plane of the U-shaped member and to one side of the vertical plane thereof. Obviously when the butt end of 15 the whip is back against the rear end of the body, that portion of the whip engaging the U-shaped member 15' will be of comparatively small diameter thus allowing the hook to drop low enough where it will clear 20 the lower edge of the seat support, thus permitting the door to be readily opened if closed, or closed if open. Any attempt to draw the whip out from its position in the U-shaped member will bring the butt end of 25 the same toward the U-shaped member, thus raising the hook to a position higher than the lower edge of the seat support which will obviously preclude opening of the door until the hook is permitted to drop to a 30 lower position as above stated.

From the foregoing description and the accompanying drawings it is believed that a clear enough understanding of the invention is to be had to render further description unnecessary.

The invention having been described, what is claimed as new and useful is:

1. The combination with a buggy body having a seat supporting means disposed substantially intermediate its length, of a 40 cover member hingedly attached to the seat supporting means and swinging down to a position of a closure for that part of the body behind said means, a hingedly mounted door carried in the body and movable to a position of closure for that portion of the body which the cover member closes, a flexible member connected with said cover member, and a locking means for said door, the 45 flexible member being engageable with said locking means.

2. The combination with a buggy body having a seat supporting means disposed substantially intermediate its length, of a 55 cover member hingedly attached to the seat supporting means and swinging down to a position of closure for that part of the body behind said means, a hingedly mounted door carried in the body and movable to a 60 position of closure for that portion of the body which the cover member closes, a flexible member having one end attached to said cover member, pulleys carried on the bottom of the said body, the flexible member being trained over said pulleys, and a

locking device for said door, the said flexible member passing through an opening formed in said door and being engageable with said locking means.

3. The combination with a buggy body 70 having a seat supporting means disposed substantially intermediate its length, of a cover member hingedly attached to the seat supporting means and swinging down to a position of closure for that part of the 75 body behind said means, a hingedly mounted door carried in the body and movable to a position of closure for that portion of the body which the cover member closes, a flexible member having one end attached to said 80 cover member substantially at an intermediate point adjacent that edge opposite the hinged edge, pulleys carried by the said body over which said flexible member is trained, a locking device for said door, the 85 flexible member passing through an opening of said door and being engageable with said locking means, and other flexible members each having one end attached to the cover member adjacent a corner opposite the 90 hinged edge and the other end connected with the first said flexible member.

4. The combination with a buggy body having a seat supporting means disposed substantially intermediate its length, of a 95 cover member hingedly attached to the seat supporting means and swinging down to a position of closure for that part of the body behind said means, a hingedly mounted door carried in the body and movable to a position of closure for that portion of the body which the cover member closes, a flexible member having one end attached to said 100 cover member substantially at an intermediate point adjacent that edge opposite the hinged edge, pulleys carried by the said body over which said flexible member is trained, a locking device for said door, the flexible member passing through an opening of said door and being engageable with said 105 locking means, other flexible members each having one end attached to the cover member adjacent a corner opposite the hinged edge and the other end connected with the first said flexible member, and a snap included in the first said flexible member 110 whereby it may be separated for the purpose specified.

5. The combination with a buggy body having a seat supporting means disposed 120 substantially intermediate its length, of a cover member hingedly attached to the seat supporting means and swinging down to a position of closure for that part of the body behind said means, a hingedly mounted door 125 carried in the body and movable to a position of closure for that portion of the body which the cover member closes, a flexible member having one end attached to said cover member substantially at an interme- 130

diate point adjacent that edge opposite the hinged edge, pulleys carried by the said body over which said flexible member is trained, a locking device for said door, the flexible member passing through an opening of said door and being engageable with said locking means, other flexible members each having one end attached to the cover member

adjacent a corner opposite the hinged edge and the other end connected with the first 10 said flexible member, a snap included in the first said flexible member whereby it may be separated, and means carried by said door whereby a whip may be locked therewith.

In testimony whereof I affix my signature. 15
FREDRICK TUCKER.
